(57) **CLAIM**

The ornamental design for a refill head for a toothbrush, as shown and described.

DESCRIPTION

FIG. 1 is a bottom, rear and left side perspective view of a refill head for a toothbrush, according to the new design; FIG. 2 is a top, front and right side perspective view thereof; FIG. 3 is a rear elevation view thereof; FIG. 4 is a front elevation view thereof; FIG. 5 is a left side elevation view thereof; FIG. 6 is a right side elevation view thereof; FIG. 7 is an enlarged top plan view thereof; and, FIG. 8 is an enlarged bottom plan view thereof. The dashed broken lines illustrate portions of the refill head for an oral care implement that form no part of the claimed design. The dot-dash broken lines define the bounds of the claimed design and form no part thereof.
